UNITED STATES PATENT OFFICE.

MELVILLE E. PETERS, GEORGE H. FATH, AND ALBERT F. MILLER, OF DENVER, COLORADO, ASSIGNORS TO THE PETERS PATENT RIGHTS COMPANY, OF DENVER, COLORADO, A CORPORATION OF COLORADO.

AUTOMATICALLY-OPERATING BLANK OR LABEL FEEDING MECHANISM FOR BLANK-GUMMING MACHINES.

1,235,500.

Specification of Letters Patent. Patented July 31, 1917.

Application filed September 25, 1916. Serial No. 122,062.

To all whom it may concern:

Be it known that we, MELVILLE E. PETERS, GEORGE H. FATH, and ALBERT F. MILLER, citizens of the United States of America, 5 residing at the city and county of Denver and State of Colorado, have invented a new and useful Automatically-Operating Blank or Label Feeding Mechanism for Blank-Gumming Machines, of which the following

10 is a specification.

Our invention relates to a new and improved automatically operating blank or label feeding mechanism for blank gumming machines, and the objects of our invention 15 are:

First; to provide means for feeding box covering blanks or labels to blank gumming machines.

Second; to provide means by which the 20 top sheet of paper of the stack of papers is separated from the stack before it is fed forward into the blank gumming machine.

Third, to provide means by which the top blank of the stack of blanks of the automatic blank feeding mechanism is first 25 wiped backwardly and thus separated from the stack of blanks before it is fed forward into the blank gumming machine, and the wiper then either pushes the separated edge

30 of the top blank or assists in pushing it forward up over suitable knife blade guides, which assists the forward movement of the drawn back top blank, as when the advance edge of the blanks is drawn back it lifts up 35 into a curved portion, and as the wiper starts forward, some of the blanks, owing to their cramped position, fly forward quickly; others are sluggish and have to be assisted forward, and in case any do not 40 move by virtue of the resilient tension, their curved-up edge is pushed by the wipers up over the knife edge of the paper separating guides.

Fourth; to provide means for automatically feeding a stack of paper, blanks or labels up to the level of the separator, and also to the blank feeding mechanism as fast as they are fed into the gumming machine from the top of the stack.

Fifth; to provide an automatically operating paper or box wrapping blank or label feeding mechanism, the feeding movement of which is controlled by the blank gumming, conveying, transmitting and delivering mechanism of the gumming machine. 50 55

We attain these objects by the mechanism illustrated in the accompanying drawings, in which:

Figure 1 illustrates a side elevation of a paper blank or label separating mechanism 60 that is adapted to separate the top blank or label from a stack of blanks or labels.

Fig. 2 is a front elevation of the same.

Fig. 3 is a plan view thereof.

Fig. 4 is an enlarged detail sectional view, 65 illustrating the pneumatic blank feeding and separating mechanism and the actuating mechanism therefor.

Fig. 5 is a plan view of the pneumatic blank feeding device and its supporting and 70 actuating bar.

Fig. 6 is a fragmental front view showing parts not clearly shown in Fig. 2.

Fig. 7 is a rear view of the upper portion of the rear stack guide showing the blank 75 holding clips in position thereon; and

Fig. 8 is a sectional view through one of the air suction blank transferring tubes.

Similar letters of reference refer to similar parts throughout the several views. 80

Referring to the drawings:

The numeral 1 designates a shaft which extends across the machine and is journaled in the side frames 2 and 3. Upon this shaft we secure a large gear 4. This gear meshes 85 with a rack bar 5, which is reciprocally mounted in a suitable bearing 6, that is formed on the lower edge of a casing 7, that surrounds the gear 4. This casing forms a part of a horizontal bar 8, upon which a 90 stack guide 9 is adjustably and slidably mounted. This stack guide is adapted to be set against the back of the stack of blanks, and we call it the stack back guide. On the front side of the casing a bracket 11 is 95 formed, which is bolted to a cross bar 13, which is bolted to the side frames. To the cross bar are bolted two vertical slideways

10. These slideways are spaced a short distance apart, and in each a vertical bar 12 is slidably mounted. The top of the bracket 11 is secured to the underside of the cross bar 13, which extends across the machine and is secured to its side frames.

10 The upper ends of the bars 12 are provided with gear teeth which extend for several inches down their outer sides, and to their lower face ends a flat bar 15, which we call a tamping shoe, is removably secured. This tamping shoe moves up and down and intermittently rests on top of the stack of blanks 16, which stack rests on 15 top of a vertical moving table 111, which has an intermittent vertical feeding movement which is automatically controlled by the demand of the top sheet feeding mechanism, as will be presently described. The gear toothed rack portions of the upper ends of 20 these vertical bars mesh with two pinions 17, which are mounted on a shaft 18, that is journaled in the opposite side frames. This shaft extends beyond the frame 3 and to this 25 end of the shaft a rock arm 19 is secured, one end of which rests on top of a vertically disposed rod 20, which we call the stack table's feeding rod. To the opposite end of this rock arm is pivotally connected a pup- 30 pet 21, in which is slidably mounted the upper end of a connecting rod 22, the other end of which is connected to one end of a rock lever 23, to be hereinafter mentioned.

At a short distance in front of the shaft 35 18, a square shaft 24 extends across the machine and is journaled in suitable bushings that are mounted in the side frames of the machine. On this square shaft we mount two levers 25, which we call friction-feed 40 toe levers, and which are provided with square apertures that fit slidably on the shaft. These levers depend vertically from the shaft and are adjustably secured to it by set screws 26, at any desired distance 45 from the center of the machine. The lower ends of these levers are turned at right angles inwardly from its vertical portion and to these ends double ended rock arms 27 are pivotally secured, and from their pivoted 50 ends two arms 28 and 29 extend in the same forward direction, but at an angle to each other. The lower arm 29 is provided at its lower end with a soft shoe 30 of rubber or other suitable material, which engages the 55 top paper or blank of the stack of papers or blanks, the advance edges of which are confined under knife edge clips 31, and moves backwardly as will be presently described. The other arm 28 of each rock arm 60 is pivotally secured to the lower forked end of a rod 32, the upper end of which extends loosely through a lug 33, that is formed on the side of the friction toe lever 25. The 65 top end of this rod is threaded and a knurled finger nut 34 is threaded to it. By means

of this adjustable rod 32, the resilient bearing tension or pressure of the shoe 30 against the top paper or blank is regulated to suit papers or blanks of different sizes.

The knife edge clips 31 are preferably in 70 the form of thin blades that taper from a rounded end to thin knife edges, and their rounded ends are apertured and are hinged between the bifurcated ends of blocks 35, which are secured to one side of a plate 36, 75 that extends across the machine between the frames and is secured to them and forms the front blank guide, as will be hereinafter explained. These knife edge clips are arranged to set down against the top of the 80 stack of blanks which is being constantly fed up against them. The upper edge of the plate 36 is preferably provided with a number of independent notches or recesses 37, that are preferably separated from each 85 other, and each knife edge clip lies in one of the recesses. The clips are adapted to be moved either inwardly or outwardly from the longitudinal center of the machine, as desired, to fit different sized blanks, and the 90 distances between the centers of these recesses of the supporting plate 36 represent the progressive sizes of the group of blanks the machine will feed and coat with gum.

Each clip is hinged to its block 35 by a 95 pin 38 which passes through the clip and loosely through the bifurcated end of the block, the clip being secured upon the pin. One end of the pin extends a suitable distance beyond the side of the block, and a 100 collar 39 is rigidly secured thereon. A coil spring 40 surrounds the pin between the collar and the adjacent side of the block; and one end of this spring is secured to the 105 block, and the other to the collar, whereby the clip is held against the top blank under resilient pressure sufficient for the required purpose.

The blanks are arranged in predetermined 110 sizes that vary from about two inches wide by four inches long to about twelve inches wide by twenty inches long, and the knife edge clips can be moved to guide the advancing edge of the different sized blanks 115 relatively to a pair of air suction tubes to be presently described, which are also arranged to be moved to fit the different sized blanks. The tamping bar moves down against the top of the stack of blanks first; then instantly afterward the wipers draw the top 120 blank from under the clips. Consequently the advancing edges of all sizes of blanks when drawn back are drawn from under the knife edge clips by the wipers and when released, instantly spring forward and run up over the knife edge of these blank separating clips, the under side of which rests directly on top of the stack of blanks, the pressure of the clips upon the blanks 125 being sufficient to prevent the separated 130

blank from moving back under the knife edge clips. Consequently it moves up over them. The instant the advancing edge of the blank moves up over the knife edge clips 5 the tamping bar rises and releases its pressure against the top blank, as well as against the stack of blanks.

The top blank now having been separated from the stack of blanks, and its advance 10 edge correctly alined at exactly right angles to the center of the machine, the top separated blank is ready to be advanced from the stack to the feed roller of the gumming machine.

15 This feature of our invention we preferably carry out in the following manner and by the following described air suction blank gripping force and mechanism:

The inner end of the horizontally arranged rack bar 5 is provided with a short 20 vertically arranged slideway head 44, which is removably secured to it, and in which a cross-head 45 is reciprocally mounted. The top of this cross-head is provided with a 25 roller 46, which is engaged by the outer end of a finger 47, the inner end of which is secured upon a shaft 48, one end of which is pivotally mounted in the side frame 2, the other end being pivotally secured to a 30 lug that is formed on the adjacent end of the gear casing 7; to the lower end of this cross-head 45 a sleeve member 49 is secured by screws 50. This sleeve is provided with an axial aperture that extends through it, 35 and at the opposite ends of the sleeve, split clamping lugs 51 are formed, in which clamping screws are threaded. And in the opposite ends of the sleeve, tubes 52 are inserted and are clampingly secured to the 40 sleeve by the clamping screws.

This arrangement permits the tubes to be quickly removed and shorter or longer ones to be inserted in their place, although the tubes 52 can be moved in and out of the 45 sleeve a short distance and clamped in adjusted positions.

This sleeve and its end tubes form the air suction reservoir for two air suction blank gripping tubular members 53 that are arranged to be moved down on the top blank and grip it with an air suction drawing force, as will be presently explained. We 50 preferably illustrate but two of these air suction blank gripping tubular members, but 55 more or less of them may be used if desired. These two air suction tubular members are mounted on the opposite ends of the air reservoir pipe 52, and they comprise arms that are secured at one end on the end of 60 the air tubes 52. These arms are each provided with a passage 54 that is connected at one end with the air tubes 52, and at its other end with an air suction blank gripping tubular plug 55, which is made of steel 65 and is arranged to be set up into a cup mem-

ber 56 on the end of the arms. These steel plugs project slightly below the outer ends of the arms, and a thin, soft, rubber disk 57 is secured to the end of each cup by any suitable means, preferably by a flange portion 58, that is formed on the outer ends of the plug and is arranged to clamp the central portion of the rubber disk against the end of the cup 56.

To the center of the sleeve a pipe 59 is 75 connected to an aperture that extends into the axial aperture of the sleeve. This pipe extends upwardly a short distance and then is bent to extend laterally to one side of the machine, where it is connected to one 80 end of a pipe or tube 60, the opposite end of which is connected to an inlet nipple that is threaded to the inlet aperture of an air pump 61, that is secured to the base plate of the machine.

This air pump is provided with a connecting rod and piston 62, that is connected to one end of a rock arm 63; the opposite end of this rock arm is pivotally connected to a cross shaft 64, of the machine. The rock 90 arm is provided with a roller 65, intermediate of its ends which is arranged to engage a cam 66 that is formed on one side of a disk 67, that is secured on a shaft 68, that forms one of the main driving shafts of the 95 machine.

This air pump is timed in such relative 100 relation to the blank feeding movements of the feed and gumming rolls that it causes the air suction tubes to grip by air suction 105 a blank, and advancingly feed it forward to the blank feeding roller where these air suction tubes deposit it, as will be presently described, and where the air suction force is broken by the reverse stroke of the pump 110 piston, which causes an air pressure in the pipes and air suction tubes, or if preferred, the pump is arranged to neutralize the suction force to cause them to instantly release the blank at the blank feeding roller 115 69, the instant the air suction inlet apertures 70 of the feed roller 69 grip it.

The air suction tubes are normally held at about an inch above the top sheet of the stack of blanks by a pair of springs 71, that 115 are connected at their upper ends to the bent-over ends of two strips 72 that are secured to the opposite sides of the slideway head 44, and at their lower ends are secured to the opposite ends of a spanner 120 bar 73 that extends across the under side of the slideway head and beyond it far enough on each side to receive in apertures the opposite ends of the two springs 71. These springs are contraction springs and 125 they normally hold the cross-head through the medium of the spanner bar up even with the lower edge of the slideway head. These air suction tubes are moved down against the top sheet of the stack of blanks by the 130

finger 47, which is reciprocated intermittently by the shaft 48, on which the finger is secured. This shaft extends from the finger to the side frame 2, in which it is journaled.

Upon this shaft one end of a lever 74 is secured, the opposite end of which is pivotally connected to one end of a connecting rod 75, the opposite end of which is pivotally secured to one end of a lever 76, the opposite end of which is secured on a shaft 77, which extends across the machine and is journaled in the opposite frames thereof.

Upon the opposite end of this shaft a lever 78 is secured, the free end of which is provided with a roller which engages a cam 79, that is formed on one side of a disk 80, that is secured on one of the cam shafts 68 of the machine. This cam, through the medium of the levers, imparts a swinging oscillating movement to the finger 47 and this movement is timed to cause the finger to move the cross-head and the sleeve and the air suction blank gripping tubes downward until the air suction tubes bear against the top blank of the stack of blanks when the air pump operates to create an air suction force in these tubes, which grips the blanks tightly to them. The finger then allows the cross-head to move upward in the slideway of the rack bar 5; then the rack bar is moved forwardly by the large gear 4, which is driven by the shaft 1, which rotates the gear 4 in the following manner: This shaft extends beyond the side frame 2, and on this end of it a pinion 81 is secured, which is engaged by a segment gear 82 that forms one end of a rock arm 83. This rock arm is mounted on a stud pin that is secured to the adjacent side frame 2. The opposite end of the rock arm is pivotally connected to one end of a connecting rod 84, the other end of which is connected to a lever 85, that is secured to a stud shaft 86 that is journaled in the frame and extends through into the machine far enough to receive one end of a lever 87, which is secured to it. The opposite end of this lever 87 is provided with a roller which engages a cam 88 that is formed on one side of a disk 89 that is secured on one of the cam shafts 68 of the machine.

This mechanism rotates the large gear and causes it to move the rack bar 5 forwardly far enough to cause the air suction blank gripping tubes to carry the advance edge of the blank over and to deposit it down against the transverse row of air suction inlet gripping apertures 70, which are formed in the peripheral surface of the feed roller 69. The finger 47 at this point again engages the roller of the cross-head and moving it down with the air suction tubes 55 directly against these air suction blank gripping apertures with sufficient pressure to

force the advancing edge of the blank tightly against the air suction inlet blank gripping apertures to firmly grip the advancing edge of the blank firmly to the feed roller.

As the blanks are fed rapidly by the air suction tubes to the blank feeding roller, it sometimes happens that a blank will get out of alignment before it has arrived at the air suction blank gripping apertures of the feed roller, either from imperfect gripping contact of the air suction tubes and the air suction drawing force or from some other cause. In such cases it is necessary that the out of alignment blank be instantly removed.

There are a number of ways in which this feature of our invention can be carried out. We preferably, however, arrange this feature in the following manner: At a convenient point between the knife edge clips 35 and the air suction air inlet apertures of the feed roller, and preferably in substantially the same horizontal plane as the top of the stack of blanks, as defined by the knife edge clips, we position at a short distance apart two shafts 90 and 91, upon which we mount rollers 92, preferably of rubber, which are arranged to meet and bear against each other in the center between them. These rollers are short rollers that are positioned at equal distances apart on opposite sides of the center of the machine and a space is left between them. A vertically reciprocating blade 93 is mounted above them and is arranged to be moved down between them and thus engage a blank that gets out of alignment before it reaches the feed roller, and is consequently not caught by the air suction of said roller, and then this blade carries it down between the rollers which are constantly rotating toward each other, and they then feed it down through them and out of the way.

These blank engaging rollers 92 are rotated toward each other by a pair of pinions 94, of the same size that are secured on one end of the shafts 90 and 91, and mesh into each other. And on the opposite end of the shaft 90 a round-belt sheave 95 is secured. A round belt 96 is mounted on this sheave, 110 and extends to and around a sheave 97 that is rotatively mounted on a stud shaft that is secured to the outside of the adjacent side frame 2. A bevel gear 98 is secured to the outside of the belt sheave 97, and meshes 115 with a similar sized bevel gear 99, that is secured on the main clutch controlled and belt driven driving shaft 100 of the machine, which shaft extends parallel with the longitudinal center of the blank gumming machine and is journaled in suitable bearings 125 on the outside of the adjacent side frame.

The vertically reciprocating blade 93 comprises a thin straight strip of metal that extends transversely across the machine be- 130

tween and close to its side frames, where it is secured at its opposite ends to vertical bars 101, each of which is reciprocally mounted in two slideway bearings 102, that are secured to the top and bottom and adjacent inside surfaces of the side frames.

These vertical bars are reciprocated by cam actuated levers 103, one end of each of which is mounted on a shaft 104, which extends across the machine and is journaled in its side frames. The outer ends of these levers are pivotally connected to the ends of connecting rods 105, the opposite ends of which are pivotally connected to the vertical bars 101. A lever 106 is secured on the shaft 104, the free end of which is provided with a roller that engages a cam 107 that is formed on one side of a disk 108, that is secured on the shaft 68. The cam is timed to impart a reciprocative movement to the ejector bar of sufficient stroke to hold it and cause it to normally stand above and to move down and engage every blank that accidentally gets out of proper alignment while being picked up and fed to the feed roller by the air suction blank gripping tubes.

The blank engaging edge of the blank ejecting blade is provided with recesses 109 that are arranged to allow its intermediate edges to extend down centrally between the ends of the rollers 92, and also down between the shafts beyond the rollers far enough to permit its lower edges to push the blank between the rollers to their meeting centers, so that the rollers will rigidly and quickly grip them, while the recesses in the edge of the blade extend above the meeting centers of the rollers and do not engage the blank.

40 The blank feeding roller 69 is an intermittent rotating feed roller and it feeds the blanks one at a time to a blank gumming cylinder 110, as will be presently described.

The stack of blanks that are fed one at a time to the feed roller and to the gumming cylinder are supported on a table 111, which stands in a horizontal plane. This table comprises a flat smoothed top table that is provided with sliding lugs at its opposite ends, which rest in slideways that are formed in the inside surfaces of the side frames of the machine.

This table is adapted to be fed upwardly intermittently by mechanism that is substantially the same as the mechanism illustrated in our pending patent, Serial Number 30,471, filed May 25, 1915, for a blank gumming machine.

We will, however, describe the present arrangement, which is as follows:

45 A shaft 112 extends across the frame and is journaled in the side frames at the forward end of the machine. Upon this shaft two bevel gears 113 are mounted, one at each end, and above these bevel gears there are

two other bevel gears 114, that are secured to the ends of vertical shafts 115, that mesh with the bevel gears 113 on the cross shaft 112.

The vertical rods are rotatively supported in suitable bearings 116 that are secured to the insides of the side frames. The upper ends of these vertical rods are threaded and they thread into and through threaded bushings 117, that are screwed into apertures formed in the table to receive them. These threaded rods are held from up or down movement in their supporting lugs by collars 118, and the hubs of the gears. Consequently when the cross shaft is rotated its gears 113 rotate the gears 114 and the vertical shafts 115, in the threaded bushings of the table, which moves the table up or down, depending on which way the cross shaft is turned. This cross shaft extends through and beyond the right hand side frame far enough to receive a hand turning wheel 119 that is secured to it and a pawl and ratchet mechanism which is arranged to rotate this shaft in short step by step movements automatically by the blank feeding mechanism as the blanks are needed at the top of the stack.

20 The blank feeding mechanism is arranged to feed several blanks off from the top of the stack when the stack of blanks has been fed up against the under side of the knife edge guides by the table, and the blank feeding mechanism will feed several predetermined numbers of blanks off from the top of the stack before it starts the mechanism that rotates the cross-shaft 112, that feeds the table upwardly.

The coöperative action between the blank feeding mechanism and the table is as follows: The blank edge wipers 30 that move the advance edge of the blank back from under the knife edge clips have, through their vertical resilient tension tread an adjustable up and down movement independent of the upward feeding movement of the table and blanks sufficient to feed a number of blanks off of the top of the stack of blanks without any upward feeding movement of the table, while feeding several of the blanks, assuming that the wipers are started on top of the stack just after the stack has been fed up against the under side of the knife edge clip by the table and before the table commences to feed the stack of blanks upwardly within the engaging reach of the wipers.

The air suction blank gripping tubes also have a vertical feed movement of the same variable blank engaging and feeding stroke movement, relative to the feeding movements of the table, but acting independent of it when standing at the top of the stack when it has been fed up under the knife edge blank holding clips, and these two blank separat-

ing and feeding mechanisms coöperatively act to start the table to feeding the stack of blanks upwardly as they near the end of their downwardly feeding movement which, 5 for example, has been predeterminedly adjusted and arranged to feed ten blanks off of the top of the stack before they start the mechanism that operates the table to feed the stack of blanks upwardly close against 10 the under side of the knife edge clips.

The mechanism that connects the blank separating and feeding mechanism to the cross shaft of the table is as follows: The lower end of the rod 20 extends slidably 15 through a supporting guide 120 that is secured to the side of the adjacent side frame of the machine, and its lower end rests on top of a flat lug portion that is formed on one end of a rock arm 121, that is pivotally 20 secured intermediate of its ends to the side of the adjacent side frame. The opposite end of this rock arm is pivotally connected to one end of a link 122, the opposite end of which is pivotally connected to the lower 25 side of a disk 123 that is loosely mounted on the cross shaft 112 at the side of a ratchet wheel 124 that is secured on the shaft. This disk has a smooth peripheral edge that is free from ratchet teeth and that is enough 30 larger in diameter than the ratchet wheel to be normally engaged by a pawl 125, which normally rests on top of it. This disk is provided in its peripheral edge with a recess 126, that is long enough to equal several of 35 the teeth of the ratchet wheel, and the pawl which normally rests on the peripheral edge of this disk cannot engage the teeth of the ratchet wheel, except the disk be moved so that its recess 126 will register opposite to 40 the tooth engaging end of the pawl. This it is caused to do by the following described mechanism operating in the following described manner:

The rock arm 121 is operated to turn the 45 disk 123 so that its recess 126 will register opposite to the ratchet teeth engaging end of the pawl, by the reciprocal movement of the rod 20, the upper end of which is engaged by one end of the rock arm 19, the other 50 member of which carries the eye bolt 21, through which the rod 22 passes. The upper end of the rod receives a nut 127, between which and the eye bolt 21 is interposed a coil spring 128, which exerts a yielding 55 pressure on the eye bolt 21, when the rod 22 is drawn downward, and a collar 129 on the said rod engages the said eye bolt on the upward movement of the rod. The lower end of this rod 22 is connected to one end of 60 the rock arm 123, that is rigidly mounted on a shaft 130, which is journaled in the side frames of the machine. Upon this shaft is also rigidly secured an arm 131 which is provided with a roller that engages a cam 132 65 on the other side of the disk 123 that is se-

cured on the shaft 68. This cam reciprocates the rod 22 and rock arm 19 and causes it to strike against the upper end of the rod 20, which tilts the rock arm 121, causing it to draw the link 122 to turn the disk 123 on the shaft 112, which brings its recess in alignment with the ratchet teeth engaging end of the pawl, and allows it to engage the ratchet teeth and to turn the ratchet toothed wheel 124, and consequently the shaft 112, 75 which raises the table. A spring 133 is secured to the rock arm 121, and to the adjacent side frame, which is arranged to draw the rock arm back to its normal position between each of its disk turning movements. 80

The upper end of the rod 20 is slidably supported in a lug 134, that is secured to the adjacent side frame of the machine. The oscillating movement of this rock arm and of the shaft 18 causes the gears 17 which are 85 mounted on the shaft and which mesh into the teeth of the rack bars 12, to reciprocate the stack tamping bar 15, the reciprocal movements of which are timed relative to those of the other coöperating blank feeding 90 parts.

A hub 135 is mounted loosely on the shaft 112, at the side of the ratchet wheel, and this hub is provided with a projecting arm 136. The pawl 125 is secured to this arm by a 95 pin 137, to which a spring 138 is secured in such a manner as to hold the pawl in engaging relation to the teeth of the ratchet wheel. To the outer end of this arm one end of a connecting rod 139 is secured, the 100 opposite end of which is secured to one end of a rock arm 140. This rock arm is secured intermediate of its ends to a stub shaft 141, that is journaled in the adjacent side frame of the machine. The opposite end of this 105 rock arm is connected to one end of a connecting rod 142, that is connected at its opposite end to one end of a lever 143, that is secured on one end of the square shaft 24. On the inner end of the stub shaft 141 one 110 end of a lever 144 is secured, the opposite end of which is provided with a roller 145 that engages a cam 146, that is formed on one side of the disk 123, that is secured on the cam shaft 68. This cam actuates 115 through the medium of the rock arm 140 and the connecting rod 142, the wipers 30 that draw the blanks one at a time from under the knife edge clips and at the same time the rock arm 140 moves, through the medium of 120 the projecting arm of the pawl 125, and its supporting hub to move the said pawl to engage the ratchet teeth of the ratchet wheel to turn the cross shaft and consequently to 125 raise the table and the stack of blanks.

A right and left handed threaded rod 147 is extended across the machine and is journaled in the side frames, beyond one of which one end of the rod extends, and a hand turning crank 148 is secured to its end. 130

Double ended levers 149 are threaded to the opposite threaded ends of these right and left handed threaded rods, and the lower ends of these double ended levers are 5 loosely and slidably mounted on a smooth cross rod 150, that is secured to the side frames. This smooth rod acts as a horizontal guide for the threaded double ended levers 149. The upper ends of these double 10 ended levers are each provided with a rectangular bar 151, that extends vertically upward through lateral slots 152, formed in the side edges of the table, which slots extend from the sides of the table to near 15 enough to the center of its width to allow these vertical bars to be fed along the threaded rod toward the center of the table far enough to act as side guides to the smallest size blanks the machine will coat with 20 gum.

These vertical rods act as side guides for all of the different sizes of blanks the machine will coat with gum, and they are fed laterally toward or away from the center of 25 the table until they fit against the sides of the stack of blanks. As these slots 152 in the table are wide, we bridge them over with thin plates 153, that are seated in a stepped recess that is formed in the upper 30 edge of the slot to receive them. These plates are made to slide freely in the steps of the recesses and they are each provided with an aperture through which the vertical bars extend. The upper ends of these bars 35 extend slightly above the knife edge clips 31.

The operation of our improved blank feeding mechanism for separating and feeding blanks one at a time from a stack of blanks to the blank controlling and gumming mechanism of a blank gumming machine is as follows:

Assuming that the friction clutch pulley has been properly belted to a source of rotative power which is transmitted to the cams 45 through suitable connecting mechanism, and a stack of box wrapping blanks is placed on the table and fills the space between the table and the under side of the knife edge clips and the side bars have been moved in against 50 the opposite side of the blanks by the threaded rod 147, and that the back end stack supporting plate 9 has been moved on the bar 8, up against the back end of the stack of blanks; then when the machine is started to 55 running the tamping bar first moves down on top of the stack of blanks with pressure enough to hold the first blank from slipping backward when instantly afterward the wipers 30 swing over and down against the 60 advance edge of the top blank and move it backwardly from under the knife edge clips, and then releases it, and instantly afterward the air suction operating blank gripping tubes 56 move down against the advancing edge of the blank and grip it and

raise it and then feed it forward over the transverse row of air suction inlet apertures 70, in the peripheral surface of the feed roller 69, when the suction grip of these tubes on the blank is broken by the reversing 70 of the suction stroke of the cam actuated piston of the air pump that creates the air suction in the blank gripping tubes.

The large thin rubber disks 57, at the entrance of these tubes rest flat against the top 75 of the blank, and the air suction force draws their soft flexible flange down tight against the blank and prevents any possibility of any air from entering under them. Consequently a perfect vacuum is established in 80 the tubes, which grips the blanks tightly and conveys them quickly to the feed roller, the forward feeding movement of these tubes being effected by the large gear 4, moving the rack bar and the supporting sleeve 49, 85 and the air suction blank gripping tubes forward. In case a blank does, from any cause whatsoever, become disarranged so that its advance edge does not fully cover the transverse row of blank gripping air suction apertures in the feed roller, the suction in the feed roller is broken and then the feed roller makes its intermittent rotating movement without the blank, and the air suction tubes having been quickly returned for another 90 blank, the cam and lever actuated blank ejecting blade moves quickly down against the blank and pushes it down between the ejecting rollers 92, which very quickly feed it through them out of the path of the next 100 blank and under the machine.

Our invention, while especially adapted to feeding blanks for covering boxes to our above mentioned application, is also adapted to feed square sheets of paper or labels, 105 with or without printed matter on them, to any kind or character of gumming machinery or to printing and other pressing when it is desired to subject them to further treatment, and while we have described the 110 preferred construction and arrangement of our improved paper and label feeding mechanism, we do not wish to be limited to it, as many changes might be made without departing from the spirit of our invention. 115

Having described our invention, what we claim as new and desire to secure by Letters Patent, is:

1. An automatic stack of blank feeding mechanism, comprising means including an 120 upwardly feeding table, resiliently yielding knife edge clip members extending over and bearing on the advancing edge of the blanks, an intermittent operating presser device for engaging the top of the stack, rubber wipers 125 arranged to engage the top blank and draw its advance edge back from under said clips against the presser device and then to advance it over the top of the knife edge guides, and means including the air suction members 130

- comprising the plug holder, the steel plug and the soft pliable rubber disk arranged to grip and advance the top blank from the stack.
- 5 2. An automatic stack of blank feeding mechanism, comprising stack feeding means, stack holding means, means for feeding the top blank from the stack of blanks, and means for feeding the separated blank forward to further treatment, and means including a reciprocating blade and feed rollers for ejecting the disarranged blanks from the machine.
- 15 3. An automatic stack of blank feeding mechanism, comprising the upwardly feeding stack of blank's feeding table, the resilient knife edge clip guides extending over and against the top of the stack of blanks and in engagement therewith, the tamping bar arranged to intermittently engage said stack with a holding pressure, the soft tread friction top blank engaging wipers arranged to engage the advance edge of the top blank and draw it from under the said 25 knife edge guides, and means including the air suction gripping members comprising the cups, the steel plugs within the cups, the soft rubber disks and the rack bar actuating mechanism for gripping said released blank and for advancing it to further treatment.
- 35 4. The combination in a blank feeder for stacks of blanks, of operative mechanism for separating the top blank, means for orderly alining blanks and means for stopping disorderly alined blanks and removing them, said means comprising blank gripping and feeding rollers interposed in the blank feeding mechanism, and a reciprocal blade for 40 striking the stopped disorderly alined blanks and pushing them into said rollers, whereby said rollers feed said blanks between them and discharge them from the feeding mechanism.
- 45 5. In a blank feeder, the combination of the supporting side frames with the stack of blank supporting and table mechanism and means for separating the top blank from the stack, comprising resiliently pressure yielding knife edge wedge shaped members positioned along the advancing edge of the stack of blanks and arranged to overlap and bear against the advance edge of the stack of blanks, and means for feeding 55 and keeping said stack of blanks up and against the under side of said knife edge top blank separating members, depending laterally adjustable levers on said shaft, the rock arms pivotally attached intermediate 60 of the ends to the lower ends of said levers, expansive resilient means attached to one end of said rock arm, a resilient pressure yielding frictional surfaced blank edge engaging wiper member secured to the opposite end of said rock arms and means for im- 65 parting an intermittent reciprocating movement to said top blank separating wipers.
6. In a blank feeding for gumming machines, the combination of the machine and its supporting side frames and an upwardly feeding stack of blanks, with the square cross shaft, the depending levers thereon, the rock arms pivoted thereto, the pins pivoted to one end of said rock arms, lugs on said levers through which said pins extend slidably, an expansive spring on each pin between said end of said rock arm and the adjacent side of said lug, a nut threaded to the top of each pin and bearing on said lug and arranged to adjust the expansive tension of said spring, and a blank engaging friction pad secured to the end of the opposite arm of said rock arm and arranged to bear with a frictional contact and with a yielding resilient pressure on the top blank of said upwardly feeding stack of blanks, and means including cam and lever and rock arm mechanism for imparting a reciprocal blank engaging stroke to said wipers and for feeding said stack of blanks to the operative top blank engaging reciprocal movement of said wipers.
7. In a blank feeder for blank gumming machines, the combination with the supporting side frames of the machine, of the cross shaft journaled in said frames, the gear secured thereon, the cross bar secured to said side frames, the casing surrounding said gear and secured to said cross bar, the slideway on the lower part of said casing, the rock bar reciprocally mounted in said casing's slideway and meshing with said gears, the projecting bar on said slideway, the stack supporting back holding plate slidably mounted on said projecting bar and the vertical slideway secured to the inner end of said rock bar, and means including cam and lever actuated mechanism connected to said gear supporting shaft for imparting a reversible rotating movement to said gear where said rock bar is reciprocated in its supporting slideway.
8. In a blank feeder for blank gumming machines, the combination of a reversible rotating movement gear with a stack of blank feeding mechanism, a rock bar meshing with said gear, provided with a vertical slideway on its inner end and arranged to be reciprocated in a horizontal plane by said gear, a cross head reciprocally mounted in said slideway provided with a resiliently controlled vertical reciprocal movement independent of the reciprocal movement of said rock bar, and a laterally adjustable air suction blank gripping mechanism secured to said cross head and arranged to be moved down and grip the top blank of said stack of blanks and forward it to further treatment.
9. In a blank feeding machine, the com- 130

- 5 combination of the machine's frame, the stack holding and vertically feeding table, and the stack of blanks thereon, with a horizontally reciprocating rack bar positioned above the stack of blanks, means for reciprocating said rack bar, a vertical slideway in the inner end of said bar, a cross head arranged to reciprocate vertically in said slideway, a reciprocating finger arranged to move said cross head downwardly in said slideway, means including springs secured to said slideway and arranged to draw said cross head upwardly when released from the downward movement of said finger, a tubular sleeve secured to said vertically reciprocating cross head, tubes slidably mounted in the opposite ends of said sleeve, means for securing said tubes in adjusted positions toward or away 10 from the longitudinal center of said machine, tubular arms on the outer ends of said tubes, a flexible rubber disk on the outer end of said tubes arranged to engage the advance edge of the top blank of said 15 stack of blanks, means for reciprocating said rack bar and said finger and means including an air suction force creating mechanism attached to said tubular sleeve for producing an air suction blank gripping force 20 in said blank gripping tubes, whereby the top blank of said stack is engaged by said air suction blank gripping tubes and is conveyed a predetermined distance to further treatment.
- 25 10. In a blank feeding machine, the combination of the side frames and the stack of blanks supporting table slidably mounted therein, the threaded nuts in said table, the vertical threaded rods threaded through 30 said nuts, the cross shaft journaled in said side frames and geared to said vertical rods, the lateral slots in the opposite sides of said table, the vertical blank sides supporting laterally adjustable rods extending up 35 through said slots in said table, means including the right and left hand threaded rods and the hand turning rods for moving said rods simultaneously together to and from the center of said table to fit the opposite sides and support different sized blanks on said table.
- 40 11. In a blank feeding machine, the combination of the table, its cross shafts and vertical threaded rods with a cross bar secured between said side frames adjacent to the advance edges of said stack of blanks on said table, a top blank separating guide secured to said cross bar on opposite sides of the center of said table and comprising 45 right angled members having a vertical part secured to said cross bar in predetermined positions on each side of the center of said table to fit different sized blanks and having a horizontal part comprising a wedge shaped blade tapering to a knife edge at
- 50 its outer end and means including a pawl and ratchet cam and rock arm mechanism connected to said table's cross shaft for feeding said stack of blanks up under said top blank, separating knife edge guides, a longitudinal positioned supporting bar above said stack of blanks, a rear side stack guide comprising a cross plate slidably and adjustably secured on said bar, provided with depending fingers arranged to extend 55 down over the outside of the rear side of said stack of blanks, said vertical rods and longitudinal recesses in said table arranged to receive the fingers of said rear side blank holder.
- 55 12. The combination in a blank feeding mechanism, of the upwardly feeding table, provided with recesses extending into its opposite side edges, the stack of blanks on said table and the laterally adjustable vertical blank confining and supporting rods extending up through said recesses in said table, a stepped recess in the top edge of said table's surface, and a plate slidably seated in each of said stepped recesses.
- 60 13. The combination in a blank feeding mechanism, of the reciprocating rack bar provided with a vertical slideway in its forward end, and the vertically reciprocating and horizontally moving air suction flexible disk blank gripping tubes mounted in said slideway, means including a cam and lever actuated mechanism for moving said blank gripping tubes downwardly on their blank gripping movement, and a pair of contraction springs, the upper ends of which are secured to the opposite sides respectively of said slideway, and means for connecting the opposite ends of said springs to move said tubes upwardly on the upward stroke of their reciprocal movement.
- 65 14. In a blank feeding mechanism for blank gumming machines, the combination with the horizontally reciprocating rack bar and its driving gear and cam actuated mechanism, having a vertical slideway in its advancing end, a cross head slidably mounted in said slideway, air suction blank gripping tubes secured to said cross head, a spanner bar extending across the bottom of said cross head, and extending beyond its opposite sides, and a contraction spring secured to each end of said bar at one end, and means for securing the upper end of each contraction spring in proper position to the opposite edges of said slideway, whereby said cross head and air tubes are normally held by resilient tension of the top of their reciprocal stroke movement, a roller mounted in the top of said cross head, and means including a cam and lever actuated finger lever arranged to engage said roller and to move said cross head and air tubes downwardly on the blank engaging stroke of their reciprocal movement.

15. In a blank feeding mechanism for blank gumming machines, the combination of the supporting and feeding table, with the horizontally reciprocating rack bar and 5 its driving gear and cam and lever actuating mechanism, and provided with a vertical slideway at its advancing end, with the cross head vertically reciprocally mounted in said slideway, the roller at the upper end 10 of said cross head, the springs secured at one end to said cross head, the bar across the lower end secured at its ends to the opposite end of said springs, the tubular sleeve secured to said cross head and provided 15 with an air inlet and outlet aperture and the air conveying tube secured thereto, the air conveying tubes slidably secured to the opposite ends of said sleeve, said sleeve being provided with split ends, a clamping 20 bolt in said split ends arranged to clamp said air conveying tubes in predetermined positions and the tubular arms secured to the outer ends of said air conveying tubes, having a vertical aperture in their ends, a 25 tubular bushing secured in said ends and a thin flexible rubber disk secured to the outer ends of said tubular bushings, and means including a cam actuated air pump connected to said sleeve's air conveying tube 30 and arranged to produce and create an air suction force therein of sufficient strength to cause said rubber disks to grip, hold and retain blanks for a predetermined period of time while forwardly feeding them from 35 said stack to said blank gumming machine.

16. In a blank feeding mechanism, the combination with the supporting and feeding table, of the knife edge blank separating guides, arranged to form the limit of the 40 upward feeding movement of the stack of blanks and to form a coöperating feature of the means employed to separate the top blank from the stack, horizontally swinging frictional tread pad members provided with 45 a resiliently cushioning and downward feeding variable stroke movement arranged to coöperate with said knife edge guides to draw the advance edge of the top blank from under said knife edge guide and push it up 50 over its knife edge and top surface whereby each top blank is intermittently separated from said stack of blanks and is positioned to be engaged and fed forward to further treatment, means for feeding said table and 55 blanks upwardly against said knife edge guides, means for reciprocating said blank engaging pads, and an air suction blank engaging tubular member arranged to move down against the advance edge of said top 60 separated blank and grip and raise it and then feed it forward a predetermined distance and discharge it at a predetermined point where it is engaged and advanced to further treatment, and means including an

air suction force creating mechanism and a 65 cam and lever mechanism for operating said blank engaging gripping and feeding tubes.

17. In a blank feeder for blank gumming machines, a blank feeding mechanism and means including reciprocating fingers arranged to engage the advance edge of blanks and straighten them in feeding alinement, and means for removing disorderly arranged and crookedly feeding blanks, said means comprising blank gripping rollers interposed 75 in the feeding path of the blanks adjacent to said blank alinement fingers, and a reciprocating blade arranged to move into and out of the path of said blanks to said roller and arranged to strike the disorderly 80 arranged blanks and carry them into said blank feeding rollers, whereby they are fed through the rollers and discharged from the feeding mechanism, means for rotating the blank feeding rollers, and means for reciprocating said blank striking blade. 85

18. In a blank feeder, the combination with the side frames of the clutch controlled shaft, the air suction blank gripping feed roller, and the stack air suction blank supporting and feeding mechanism, and means for removing from said blank feeding roller said disorderly alined blanks before they are gripped by it, said means comprising shafts journaled in said frames, rollers on said shaft spaced at a short distance apart, idler rollers arranged in blank gripping relation to the rollers of said shaft, a sheave wheel on said shaft, a sheave wheel arranged to be rotated by said clutch controlled shaft, and a belt connecting said sheave wheels whereby said rollers are driven by said clutch controlled shaft, a reciprocating plate supported by said feed roller mounted concentrically with said feed roller and having a reciprocal movement across the feeding path of said blank to said feed roller, blade portions on said plate arranged to extend down by the ends of said blank gripping rollers below their blank gripping surfaces, and means including cam actuated rock arm mechanism operated by said cam shaft for reciprocating said plate and its blades to engage said stopped disorderly blanks and push them into said feed rollers. 95 100 105 110 115

19. In a blank feeder, the combination in blank feeding instrumentalities comprising a supporting table, feeding mechanism, the knife edge top blank separating mechanism, the top blank separating wiper mechanism and the air suction blank gripping tubes, and means including the pressed plate for holding each blank on the blank feeding roller when fed there from said stack, and means including the blank gripping rollers arranged adjacent to said blank edge scrapers, and the blades reciprocating across the feeding path of said blanks from said stack 120 125

to said feed roller for removing such blanks as are not properly fed to said blank feeding roller from said stack.

20. The combination of a blank feeder 5 with a blank feeding roller of a blank gumming machine, said blank feeder comprising a suitable supporting frame work, a reciprocally feeding table mounted on said frame work, said table being arranged and 10 adapted to hold a stack of blanks, means including a device for limiting the upward feeding movement of said stack of blanks by said table, means including vertical and reciprocal movement air suction blank gripping tubes arranged to move down against 15 said stack of blanks, grip the top one by suction, raise it up, move it horizontally forward, and deliver it against the air suction blank gripping mechanism of said gumming machine's feed roller, and means including cam operated mechanism operated 20 from the gumming machine for feeding the stack of blanks to said top blank separating mechanism, and to said air suction tubes 25 as fast as said tubes feed them to said feed roller.

21. In a blank feeder for blank gumming machines, the combination with the blank feeding roller of the gumming machine, and 30 the mechanism for supporting a stack of blanks, with the mechanism for feeding one blank at a time from the top of said stack to said feed roller, said mechanism comprising a blank separating member arranged to 35 limit the feed movement of the stack toward the feeding mechanism, means including a reciprocating blank engaging tamping bar for holding the top blank against accidental displacement from the stack, means including 40 friction members for feeding the top blank from under the blank separating device and for moving it up over it, and means including an air suction force operating set of flexible ended tubes adjustably arranged 45 to fit blanks of different sizes, and means including an air suction force producing pump connected to said tubes for producing an air suction blank gripping action in said tubes, said tubes being arranged to move 50 down on top of said separated blanks and grip them one at a time and then lift them up and to feed them forward to said blank feeding roller.

22. In a blank feeder for blank gumming 55 machines, the combination of the feed roller, the air suction tubes, the presser plate and the cut-out blade and its blank ejecting rollers, and the frame, the stack supporting table reciprocally mounted on said frame, 60 the geared cross shaft and the threaded geared shafts meshing with said cross shaft for feeding said table upwardly, the stack of blanks in said table and the knife edge

guides for limiting the feeding movement of said stack to its separate blank feeding 65 station, and the reciprocating top blank separating members, and their supporting shaft, a lever secured on said shaft, a rod secured to said lever at one end and at its opposite end to one end of a rock arm, a 70 shaft journaled in said frame, a lever on said shaft pivoted intermediate of its end to a roller on said lever, a power driven cam in engagement with the said roller, a connecting rod connected at one end to the opposite end of said rock arm, a ratchet tooth engaging pawl swingingly mounted on said 75 table's cross shaft and connected to the opposite end of said connecting rod, the ratchet wheel secured on said shaft, the recessed 80 disk mounted loosely on said cross shaft, with means including a reciprocating blank tamping bar, its supporting shaft and rock bars and operating pinions on said shaft, and the rock arm on the end of said shaft 85 having arms of unequal lengths, the shorter of which is provided with a swiveling lug, a rod extending slidably through said lug at one end, a compression spring along said lug secured at one end to said rod and bearing loosely against said lug, and an adjustable collar secured on said rod underneath said lug, whereby said rock arm's lug has a fixed movement against said collar and rod in one direction and a resilient yielding 90 movement against said rod in the opposite direction, a rock arm pivotally secured to the opposite end of said rod and pivoted intermediate of its ends to said frame, and a roller on the opposite end of said rock arm 95 in engagement with a power driven cam, the longer end of said shaft's rock arm being arranged to swing against the top of a reciprocating rod, a rock arm secured to said frame intermediate of its ends, one end of 100 which supports the opposite end of said rod, a connecting rod secured at one end to the opposite end of said rock arm, said connecting rod being connected at its opposite end to said recessed disk on said cross shaft, 105 whereby said stack of blanks is fed upwardly intermittently, the automatic operating movable downwardly resiliently feeding movement of said tamping bar and said blank separating wipers operating through 110 a predetermined downward feeding stroke movement which intermittently feeds the stack of blanks up to them.

In testimony whereof we affix our signatures in presence of two witnesses.
